UNITED STATES PATENT OFFICE.

WILLIAM EMMETT, OF LOGANSPORT, INDIANA.

CAR-COUPING.

SPECIFICATION forming part of Letters Patent No. 328,928, dated October 27, 1885.

Application filed February 11, 1885. Serial No. 155,591. (No model.)

To all whom it may concern:

Be it known that I, WILLIAM EMMETT, of Logansport, in the county of Cass and State of Indiana, have invented a new and Improved 5 Car-Coupling, of which the following is a full, clear, and exact description.

Reference is to be had to the accompanying drawings, forming part of this specification, in which similar letters of reference indicate 10 corresponding parts in both the figures.

Figure 1 is a sectional elevation showing a part of the frame of two cars, and showing one entire coupling and a part of another, the draw-heads being shown coupled together, 15 and Fig. 2 is a front elevation of a part of the car body, the coupling and the levers attached to the body of the car for operating the coupling.

The invention will first be described in combination with the drawings, and then pointed out in the claims.

A A represent the draw-bars of my new car-coupling. These are each cast in one solid piece of metal, with the shank *a*, coupling-head *a'*, and weight *a''* formed upon the lower side of the shank *a*. The coupling-heads *a'* are each recessed, as shown at *b*, to form two opposite claws, *c c*, the metal of the draw-head being removed at the center to form a 30 cavity, *b*, between the claws *c*. The outer surfaces of the claws *c* are rounded, as shown at *c'*, Fig. 1, and the cavities between the claws *c c* are concaved, as shown at *c''*, Fig. 1, to form cams, so that when two cars having these 35 couplings are brought together the action of the cams *c''* upon the rounded surface *c'* of the claws *c* will cause the draw-heads and draw-bars of the two couplings to be slightly rotated in opposite directions, which will cause 40 the claws *c* of the opposite draw-heads to engage each other, and thus effect the coupling of the cars without the use of springs, pins, or other separate devices.

Each draw-bar A is attached to the body of 45 the car by a keeper, B, and cross-timbers C C, through an opening in which the rear end of the draw-bar passes. A collar, *a''*, is formed upon the rear end of each draw-bar to cause it to be held by the timbers C, and each 50 draw-bar is recessed, as shown at *d*, to receive the anti-friction ball *e*. A plate or cross-bar,

D, presses against the ball *e*, being held forced forward by the heavy coiled spring E, which is attached to the heavy timber F and to the said bar D, by being placed upon the corresponding projections, *f*, so that the spring E serves as a buffer to the car. 55

The cars being coupled, in order to uncouple them it is necessary to partially rotate one or the other of the draw-bars A, so as to 60 disengage the claws *c*, and this may be accomplished from the top or platform of the car by the lever G, which is bent and fulcrumed at *g*, and acts at its lower end against a shoulder formed in the draw-head by the 65 recess *g'*; or it may be accomplished from the ground at the side of the car by the lever H, which is bent and fulcrumed at *h*, and acts at its bent end against a shoulder formed by recessing the draw-head at *h'*. By pressing the 70 outer end of the lever H downward the bent end of the said lever will turn the draw-head A, and movement of the upper end of the lever G in the direction of the arrow will have the same effect, and the rotation of the draw-bar will swing the weight *a'*, from the center, so that as soon as pressure applied by either 75 of the levers is removed the weight will act to bring the draw-head back to its original position—the position it must occupy when 80 the cars are backed together for coupling.

In bumping—that is, switching or moving cars about a depot—one of the draw-bars should be turned and held somewhat out of its natural position, so that the rounded ends 85 *c'* of the draw-heads will abut, thus preventing the cars from coupling.

In coupling it will be understood that it is only necessary to back the cars together, whereupon the claws *c* of one draw-head will 90 enter between the claws of the other, and the rounded surfaces *c'* of each draw-head will strike the concaved surface *b* of the other, which will cause the draw-heads to rotate slightly in opposite direction to cause the 95 claws *c* of the opposite draw-heads to engage with each other, as shown clearly in Fig. 1.

Constructed as described, it will be seen that the draw-bars and draw-heads are made entire in one solid piece of metal, that they 100 may be cast without a core and used without special fitting, and that no springs save the

buffer-spring E, or other separate pieces, are used about the draw-heads, thus producing a cheap, practical, and perfectly automatic car-coupling, which is perfectly reliable and not liable to get out of order.

Having thus described my invention, what I claim as new, and desire to secure by Letters Patent, is—

1. The draw-head a' , formed with the rounded claws c and concave or cam c' , for causing the draw-heads to rotate when the cars are brought together, substantially as and for the purposes set forth.

2. The draw-bar formed with a weight, a'' , in combination with the draw-head a' , having recesses $g' h'$, and operating-levers G H, the draw-head being formed with the claws c , substantially as described.

3. The draw-bar formed with the recess d , in combination with the ball e , plate D, and buffer and spring E, arranged substantially as and for the purposes set forth.

WILLIAM EMMETT.
